ATTACHING DEVICE

Filed Nov. 5, 1930

Fig. 1.

UNITED STATES PATENT OFFICE

BEN S. NELSON, OF OAK PARK, ILLINOIS

ATTACHING DEVICE

Application filed November 5, 1930. Serial No. 493,522.

My invention relates to an attaching device for a window washer's harness, and particularly to the means for securing such an attaching device to a window.

5 It has in the past, been a common practice to secure attaching devices for window washers' harnesses to the outside of the window frame by means of wood screws. In recent times many States have passed laws against 10 this dangerous practice and underwriters require that the attaching devices be anchored by bolts provided with nuts, to prevent their withdrawal from the frame. The use of 15 bolts, however, presents special problems on old as well as new structures, especially in view of the fact that the bolts must be applied so as not to mar the appearance of the window frame, and yet they must be firmly anchored in the frame.

20 An object of the invention is to provide a new and improved anchoring means for an attaching device for a window washer's harness.

25 A further object is to provide an anchoring device which does not mar the appearance of the window frame.

30 A further object is to provide an anchoring device which may be readily applied to either an old or new window frame.

35 Other objects and advantages will appear as the description proceeds.

Referring to the drawings:

Fig. 1 is a fragmentary side elevation of 35 a window frame,

Fig. 2 is a cross-sectional view taken on line 2—2 of Fig. 1, and,

Fig. 3 is a longitudinal section taken on line 3—3 of Fig. 1.

40 A window frame usually consists of parallel outer and inner boards 5 and 6, the inner board being referred to as a trim board in the carpenter trade. Between these boards is a rear board 7, and in the front of the frame is a jamb 8 parallel to the rear board. 45 These boards provide a hollow space 9 in the frame in which the sash weights and sash cords for counter-balancing the window are disposed. The outer board 5 projects beyond the jamb 8 to form one side 11 of the channel for the window sashes. On the other

side of the jamb, a stop strip 12 customarily secured to the jamb by screws 13 is provided to form another side 14 of the channel for the window sashes, and the entire channel is divided by a separator strip 15 which is set 55 in a routed groove in the jamb. An ornamental strip 16 is frequently found nailed to the outer board 5, and in some windows an ornamental strip 17 is attached to the inner side of the trim board 6.

60 In order to secure an attaching device 18 to a frame such as just described and which is representative of the standard frame found in window frame constructions, I drill a hole 19 through the ornamental strip 16, outer board 5, and extending into the jamb 8 almost to the inner edge of the jamb. This hole may extend entirely through the jamb if desired.

I next form a hole 21 in the jamb at right angles to the hole 19 and close to the inner edge of the jamb. This hole may be formed by drilling two circular holes in the jamb and cutting out the material between the holes with a keyhole saw so as to form an elongated hole 21.

A bolt 22 is then threaded through the attaching device 18 and aperture 19 so that its end terminates in the opening 21. A washer 23 and nut 24 are then attached to the end of the bolt in the opening 21.

70 When the device is applied to an old window the stop strip 12 is first removed, which may be readily done due to the fact that this stop is usually secured to the jamb by screws. In a new window construction the attaching device and bolt are secured in 75 position before the stop strip is attached to the jamb. In either case the construction is such that the hole 21 and the end of the bolt and the nut are completely concealed from view whether the window is open or 80 closed.

85 Practically all windows are provided with an opening 25 in the lower part of the inner window sash channel to provide access to the space 9 for repairing or replacing the sash cord and weight. This opening is then closed by a closure strip 26, the outer face of which is flush with the jamb so as not to interfere 90 with the movement of the window sash. This closure strip is usually made of less thick- 95

ness than the jamb as illustrated in Fig. 3. However, whether it is of the same thickness or a lesser thickness than the jamb, the inner side of the closure strip is provided with a transverse groove 27 in which the bolt 22 rests, so that the closure strip 26 may be removed without removing the bolt and attaching device from the window frame.

It will be noted that the bolt is anchored 10 deeply in the jamb. It is advisable and even essential to extend the bolt far into the jamb to provide a high safety factor. The slight weakening of the jamb by cutting out the hole 25 is compensated for by the closure 15 strip 26 which reinforces the jamb when in position in the jamb. The actual force which the bolt must resist in use, is not very great since the greatest pull on the attaching device is in a lateral direction, but the decay of 20 the wood after years of use might render the device dangerous if it were not deeply anchored.

It has been suggested to extend a bolt for anchoring the attaching device through the 25 trim board 6. However, if the end of the bolt extends beyond the face of the trim board it forms an unsightly obstruction. If the trim board is countersunk to receive the washer and nut for the end of the bolt, it 30 still leaves a deep visible hole in the face of the trim board, which is highly undesirable. Even though the countersunk hole in the trim board might be covered by an ornamental strip such as 17, these strips are usually 35 nailed securely to the trim board, and they are difficult to remove without splintering or breaking. In some of the older buildings these ornamental strips 17 are of such design that it would be impossible to duplicate them 40 in case they were destroyed in trying to remove them. The construction of this invention as described above has been found extremely practical and it is not open to the numerous objections pointed out. From the 45 artistic standpoint it in no way interferes with the design or ornamentation of the window since it is completely concealed except for the attaching device 18 on the outside of the window.

It will be understood that the embodiment 50 of the invention herein described and disclosed is merely a convenient and useful form of the invention, and that many modifications and changes may be made without departing from the spirit and scope of the invention.

What I claim as new and desire to protect by Letters Patent of the United States is:

1. A device for attachment of a window 60 washer's harness comprising a frame of parallel inner and outer boards, the inner board being a trim board, a jamb between said boards and supported thereby, said outer board and jamb having an aperture extending therethrough, an anchoring device for

the clip of the washer's harness, a bolt for securing said anchoring device in position and extending through said aperture, said jamb having an opening at right angles to the bolt aperture and adjacent the inner edge of 70 said jamb, a nut on the end of said bolt in the jamb opening, and a stop strip secured to the jamb and covering the jamb opening to conceal the opening and the end of the bolt and nut from view. 75

2. A device for attachment of a window washer's harness comprising a frame of parallel inner and outer boards, the inner board being a trim board, a jamb board between said boards and supported thereby, said jamb board having an opening for providing access to the sash cord and weights, a closure board for said opening, said outer board and jamb having an aperture therethrough, a bolt 80 extending through said aperture, an attaching device secured in position by said bolt, said jamb having an opening at right angles to said bolt aperture, a nut on the end of said bolt in said opening, said closure board having a groove for said bolt to permit removal of said board, and a stop strip secured to the jamb and covering the jamb opening to conceal the jamb opening and the end of the bolt and nut therein. 85

3. In a device for attachment of a window washer's harness, a frame having parallel inner and outer boards, a transverse rear board and a front jamb, a bolt extending through the outer board and into the jamb, said jamb having an opening at right angles to the bolt adjacent its inner edge into which the end of the bolt extends, a nut on the end of the bolt in said opening, for anchoring the bolt, an attaching device for a washer's harness held in position by said bolt on the outside of the frame, and a stop strip secured to the jamb and covering said opening to conceal the opening and the end of the bolt and nut therein. 90

4. The combination with a window frame 95

of substantially standard construction of a safety device for the attachment of a window washer's harness, said combination including a window frame having inner and outer boards, a jamb between the two boards, an inner stop strip secured to the jamb, a parting strip forming with the inner stop strip and intermediate portion of the jamb, a channel for a window sash, said outer board and jamb having an aperture extending from the outer board to a point beyond the channel, and the jamb having a side opening communicating with the aperture, a fastening device, a bolt extending through the fastening device and through the aperture into said side opening, and a nut on the bolt adapted to be reached through said side opening when said stop strip is removed, whereby the channel and inner board have an unbroken sur- 100 105 110 115 120 125 130

face, and the bolt may be inserted or renewed without removing the inner board.

5. The combination of claim 4, wherein a portion of the jamb along the channel is cut 5 away and covered by a closure strip, and said closure strip is grooved to form a channel for the bolt to permit its removal without removing the bolt.

In witness whereof I hereunto subscribe
10 my name this 13th day of October, 1930.

BEN S. NELSON.
